UNITED STATES PATENT OFFICE

ARTHUR F. JUNGERHELD, OF BRIDGEPORT, MICHIGAN

CAN COVER

Application filed January 9, 1928. Serial No. 245,290.

This invention relates to can covers of the kind commonly known as the channel and friction plug type, wherein the top of the can is fitted with an interior rim, in which 5 is formed a downwardly projecting circular groove or channel.

The ordinary function of the channel is to receive a complementary circular bead formed in the cover, so that when the cover 10 is pressed on the can its bead fits like a friction plug into the said channel of the can top.

My present invention consists in a change in the construction of the wall of the channel, whereby the objects of the invention 15 are attained.

An object is to provide, with practically no additional expense in the manufacture of the can, drainage holes in the channel 20 whereby the liquid contents, for example paint, if dropped or spilled in the channel, as nearly always occurs in the ordinary use of a paint brush, will be drained back into the can. By wiping a brush around in the 25 channel the remaining liquid can be pushed down through the drainage openings. The channel is thus cleared of all material which might otherwise harden and cake in the channel. If paint is allowed to remain in 30 the channel and harden it is impossible to properly put the cover in place again. My improvement avoids this difficulty.

A further object is to facilitate removal 35 of the cover after the groove has once been coated with the material, by preventing suction binding between the head of the cover and the channel of the can.

The holes in the bottom of the channel 40 which comprise my improvement permit air to enter the channel from within the can.

With the foregoing and certain other objects in view, which will appear later in the specifications, my invention comprises the 45 devices described and claimed and the equivalents thereof.

In the drawings Fig. 1 is a cross sectional view of the upper part of a can and cover, embodying my improvement.

Fig. 2 is a sectional view of the top rim

of the can, showing the openings in the bottom of the channel.

Fig. 3 is a part sectional bottom view of the parts shown in Fig. 2.

In the drawings numeral 1 indicates the can and 2 is the usual internal flange at the top of the can formed with the peripheral channel 3. 4 is the can cover formed with a downwardly projecting bead 5, the cover itself being of the kind commonly known as the friction-plug type of can top.

My invention consists in forming openings 6 in the walls of the channel, preferably at its bottom. The openings may be of any desired shape, although I prefer to make them in the form of elongated slots, as shown, for that form more readily permits the paint or other material to be wiped down through the groove by the simple circular wiping action of the paint brush.

The slots may be formed in any suitable way, for example, by slitting the metal and bending the edges to form downwardly projecting lips 6^a that will not cut the wiping brush 7.

I have found in practice that this simple improvement eliminates the liability of the paint or other material caking and filling the channel 3. Consequently it enables the cover to be taken off and put back repeatedly 80 while preserving the accuracy of its fit in the channel 3 and consequently the tightness of the can.

Having thus described my invention, what I claim and desire to secure by Letters 85 Patent is:

1. In combination, a plug type can cover, a can having an internal flange presenting a circumferential channel arranged to receive the plug element of said cover, the wall 90 of said channel formed in its bottom with drainage openings for clearing said channel of the contents thereof and for access of air from the can to the channel during removal of said cover.

2. A structure as set forth in claim 1 wherein the metal at the edges of said drainage openings is bent to form downwardly projecting lips.

3. In a can having a circular groove 100

formed in its rim, and a co-operating plug-type cover, the bottom of the rim formed with elongated slots having downwardly projecting lips along their longitudinal margins, said lips spaced apart to present a space into which fluid contained in the groove will be drawn by film tension.

In testimony whereof, I affix my signature.
ARTHUR F. JUNGERHELD.
